UNITED STATES PATENT OFFICE.

GEORGE A. WOODMAN, OF CHICAGO, ILLINOIS, ASSIGNOR TO WOODMAN RAILWAY SUPPLY COMPANY, OF CHICAGO, ILLINOIS, A CORPORATION OF ILLINOIS.

JOURNAL-BOX LID.

Application filed July 25, 1925. Serial No. 45,950.

Various means have been devised for resiliently maintaining closed the lids of journal boxes, the same means usually being employed to resiliently hold the lids in open position. Both coil springs and leaf springs have been used for this purpose and both have their advantages. Sometimes one is preferred and sometimes the other. A coil spring is usually considered more desirable, but it is more expensive and when it becomes broken it is difficult to replace immediately, whereas a leaf spring can usually be found with less trouble. It is therefore the object of my invention to provide a universal lid which may be employed with either type of spring.

In the accompanying drawings in which I have shown a selected embodiment of my invention;

20 Fig. 1 is an end elevation of a journal box having my improved lid applied thereto.

Fig. 2 is a section on the line 2—2 of Fig. 1 and showing the employment of a leaf spring.

25 Fig. 3 is a section on the same line as Fig. 2, but showing my invention as employed with a coil spring.

Referring now to the drawings the numeral 1 designates a journal box of any suitable construction and having hinge lugs 2 within which is received the hinge pin 3 which secures the lid 4 to the box. The hinge lugs are made in the form shown having two relative flat surfaces 5 and 6 at a substantial angle to each other and secured upon the bearing 7 on the face of the lid is a leaf spring 8 adapted to bear against the surface 5 to resiliently hold the lid closed or against the surface 6 to resiliently hold the lid open.

40 I further provide my lid 4 with a hood 9 covering and protecting the hinge lugs and hinge pin and provided on its interior with a lug 10 to receive one end of a coil spring 45 11, as shown in Fig. 3. The other end of the spring is received within a shoe 12 having a surface normally contacting with the flat surface 5, as shown in full lines in Fig. 3, and also adapted to contact with the flat surface 6, as shown in dotted lines in the same figure. This shoe is preferably provided with the recess 12' forming a grease cup to receive grease, in order to provide

proper lubrication between the shoe and the surfaces 5 and 6.

55 The spring and shoe shown in Fig. 3, as well as the hinge lug, is standard equipment, but the standard lid employing this type of spring and shoe has no means for replacing the same without taking the lid completely off the journal box, the spring being usually completely enclosed in the hood. I therefore provide the hood of my invention with the opening 13 whereby when desired the leaf spring 8 may be put in place instead of the coil spring. This is absolutely impossible with the standard hood now employed. All that is necessary to install the leaf spring in case of breakage of the coil spring, is to drill a hole for the reception of the rivet 44, 70 by means of which the spring can be secured in position, as shown in Fig. 2.

75 On the other hand when the leaf spring is preferred it may be furnished with the lid instead of the coil spring, the installation being made at the factory. When the leaf spring is initially provided with the lid, it is obvious that its presence will make it difficult to place the lid in position on the hinge pin. I therefore provide an aperture 15 in one or both of the side walls of the hood and so placed that a nail or the like can be inserted therein and will hold the leaf spring back in the position shown in dotted lines in Fig. 2. Then the lid may be readily applied to the journal box and after this is done the nail or the like, may be withdrawn, permitting the spring to take the operative position, shown in Fig. 2.

80 85 90 From the above it will be obvious that I have provided a universal journal box lid which may be readily used with either type of spring, the change from one type to the other being very readily effected. All that is necessary to replace a coil spring with a leaf spring is to drill a hole for the rivet 44 and a leaf spring may usually be improvised without a great deal of trouble. Again the lid can be readily employed for either type of spring, when the spring is to be 100 installed at the factory.

105 I am aware that changes in the form, construction and arrangement of parts may be made without departing from the spirit and without sacrificing the advantages of the invention and I reserve the right to make all

such changes as fairly fall within the scope of the following claims.

I claim:

1. As a new article of manufacture, a journal box lid comprising a body provided upon its outer side with a follower-housing projecting above the top of the body of the lid, the inner side of the housing above the top of the lid being open, the outer face of the lid being provided with a raised leaf spring seat at the open bottom end of the housing, the bottom of the housing being open to receive a leaf spring upwardly therethrough, and opposite side walls of the housing having aligned perforations to receive a rod for the purpose described.
2. A journal box having an upstanding

lug, a lid pivotally mounted on said lug and provided with a housing covering and protecting the lug, a follower mounted in said housing and in frictional engagement with the lug on the box, a coil spring bearing at one end against the back of the housing and at its other end against the rear of the follower to yieldingly hold the follower against the lug, the outer face of the lid being provided with a raised leaf spring seat below and adjacent the bottom of the housing, the bottom of the housing being open to receive a leaf spring thrust upwardly therethrough, and opposite side walls of the housing having aligned perforations for the purpose described.

GEORGE A. WOODMAN.
